UNITED STATES PATENT OFFICE.

THEODORE SCHERF, OF CLEVELAND, OHIO.

MULTIPLY PAPER.

1,250,230.

Specification of Letters Patent. Patented Dec. 18, 1917.

Application filed February 12, 1917. Serial No. 148,203.

To all whom it may concern:

Be it known that I, THEODORE SCHERF, a citizen of the United States, residing at Cleveland, in the county of Cuyahoga and State of Ohio, have invented a certain new and useful Improvement in Multiply Paper, of which the following is a full, clear, and exact description, reference being had to the accompanying drawings.

- 10 This invention relates to multi-ply paper, and more particularly to the production of such paper wherein opposed plies are reinforced by two series of threads or strips, the threads of one series extending transversely 15 of the threads of the other series. Paper of the character referred to may be used for the purpose of making bags wherein heavy material, such as plaster, may be shipped; for making linings for barrels, in which case 20 overlapping edges of the paper will be united as is the case with the selvage edges of wall paper; and also for wrapping paper for goods that it is desirable to ship in a water-proof inclosure.
- 25 In producing my paper, I prefer to use a plastic mineral adhesive, such as asphalt, for the purpose of uniting the body portions of the two sheets or plies of paper and also as the means for uniting the extreme 30 marginal edges of such sheets or plies. Where a maximum of pliability is desired in the finished product, the asphalt (or mineral adhesive) will be applied in strips, whereby the inherent pliability of the paper will be modified to a minimum extent by the use of such 35 adhesive. For the purpose of securing the maximum adhesion between the plies of a multi-ply sheet adjacent to their lateral edges as well as between the overlapping 40 edges of sheets of such multi-ply paper, I preferably interpose an animal or vegetable adhesion (such as glue or tapioca paste) between the marginal asphalt strips and the surface of asphalt inwardly spaced therefrom, whether such asphalt surface be a continuous 45 surface or a surface composed of separated strips. This animal or vegetable adhesive has the capacity of penetrating the fibers and sizing of the paper and of forming 50 a practically solid body between the two plies which it unites as well as between the two sheets of multi-ply paper which it unites.
- The last mentioned adhesive, however, is not as pliable as is a mineral adhesive, such as asphalt, and particularly where such asphalt has intermingled therewith some oily

substance, such as linseed oil or castor oil, which serves to maintain the asphalt in a plastic or semi-plastic condition and to prevent it from becoming hard or brittle as it ages and as it is exposed to cold temperatures.

The purpose of employing the asphalt at the extreme lateral edges of the sheets is threefold; it maintains in a straight condition, or under tension, the warp and weft threads that are deposited between the two sheets or plies of the paper; it contributes to the desired pliability in the finished paper; and it provides a moisture-excluding bond between the two plies of paper at the edges thereof whereby access of moisture to the space between the plies of paper at such edges will be prevented. Furthermore, the oil with which the asphalt is mingled will penetrate the paper sufficiently to prevent moisture from passing therethrough.

In the drawings forming part hereof, I have shown two forms of my paper, the manner of producing a bag bottom therefrom, the preferred kind of thread employed for reinforcing the paper, and a simple mechanism for applying the adhesive to the paper shown in Figure 1. In these drawings, Fig. 1 represents a perspective view of a piece of my multi-ply paper, one of the plies being folded back to reveal the arrangement of the threads and of the adhesive material; Fig. 2 is a similar view wherein the asphalt is applied practically continuously to the portions of the plies or sheets within the marginal edges thereof; Fig. 3 a sectional perspective detail of a bag bottom as produced from the paper shown in Fig. 1; Fig. 4 a sectional view of such bottom; Fig. 5 a perspective view of a form of reinforcing thread or strip which has been found to be particularly efficient in the production of my paper; Fig. 6 a sectional detail illustrating the manner of uniting the side or lateral edges of sheets of my paper; Fig. 7 a transverse sectional view through mechanism for applying adhesive to the paper shown in Figs. 1 and 6; and Fig. 8 a plan view of such mechanism.

Describing by reference characters the various parts illustrated herein, 1 denotes a sheet or web of paper having, between the lateral edges 2 thereof, longitudinally extending strips 3 of mineral adhesive, such as asphalt, and preferably having linseed oil

or castor oil incorporated therewith. These strips 3 serve as a means for uniting the sheet or web 1 to the opposed sheet or web and also as a means for holding the warp threads 4 against lateral displacement, because of the strong adhesion between such strips and threads. Each extreme marginal edge of the sheet or ply 1 has a strip 5 of asphalt applied thereto and, between such strip 5 and the next adjacent strip 3 there is interposed a strip 6 of animal or vegetable adhesive, such as glue or tapioca paste.

Coöperating with the sheet or web 1 is a similar sheet or web 1^a having applied thereto strips 3^a of asphalt alternating with the strips 3 on the sheet or web 1 and each strip 3^a having a warp thread 4^a embedded or partly embedded therein. The sheet 1^a is provided with the marginal asphalt strips 5^a and the adjacent strips 6^a of animal or vegetable adhesive applied in the same manner as in the case of the sheet 1.

Between the sheets 1 and 1^a are interposed the weft threads 7. In producing the multi-ply paper in accordance with my invention, I contemplate applying the weft threads in succession as the sheets 1 and 1^a approach the uniting rollers. While the other mechanisms may be employed for depositing the weft threads, I prefer the mechanism shown, described, and claimed in my application No. 98,247, filed May 18, 1916. In the operation of this machine, the weft threads 7 are maintained under tension until they are deposited upon the lower sheet or web. It is important that these threads should remain straight or under tension, and the marginal strips 5 and 5^a of asphalt have been found particularly efficient in realizing this object. The warp threads may also be fed to such uniting means in the manner shown in the aforesaid application, being so spaced as to register with the asphalt strips 3, 3^a, 5, and 5^a and to be incorporated therewith by means of the said uniting means. In Figs. 1 and 2, the parts are shown in the positions which they would occupy if the two plies were pulled apart after having been united with the warp threads adhering to their respective asphalt strips. In Fig. 2, the sheets or webs 1 and 1^a are provided with marginal asphalt strips 5 and 5^a and the adjacent strips 6 and 6^a of animal or vegetable adhesive, in the same manner as is the case with the like designated sheets or webs in Fig. 1. However, instead of applying the asphalt to the remainder of the sheets or webs in strips, I have shown each sheet or web as provided with a solid or continuous body of such asphalt 3^b, 3^c extending continuously between the strips 6 and 6^a, respectively.

In Figs. 3 and 4 I have shown the manner in which my paper may be employed for the production of bag bottoms. In these views, 65 8 and 8^a denote the opposite sides of a bag

and 9 and 9^a the side flaps. These side flaps are preferably interlocked whereby four thicknesses of multi-ply reinforced paper will be provided at the joint, and a particularly strong connection can be afforded in 70 and through the application of glue or paste (or like animal or vegetable adhesive) to the lateral interlocking edge portions of the flaps, particularly as at least one of these flaps (the one which carries the joint between the laterally connected sides of the sheet) has incorporated therewith the adhesive material 6, 6^a. The bottoms of the ends of the bag are folded in in the usual manner, as indicated at 10, 10^a and will be united 75 to the flaps 9, 9^a by suitable animal or vegetable adhesive.

In Fig. 6 there is shown, in enlarged detail, the manner in which the lateral edges of paper constructed in accordance with my invention may be united. In this view, either two multi-ply sheets, or the opposite lateral edges of the same multi-ply sheet, are shown as united by means of animal or vegetable adhesive material 6^b, which is interposed between the overlapping webs 1 and 1^a. This adhesive will penetrate the fibers and sizing of the sheets and coöperate with the like adhesive strips 6, 6^a between the plies in forming a solid bond, while the joint provided between and at the lateral edges of the plies of each sheet will be moisture-excluding by reason of the asphalt strips 5 and 5^a.

In Figs. 7 and 8, there is illustrated a simple mechanism for applying the two kinds of adhesive to the plies of the paper shown in Fig. 1. In these views 11 denotes a tank containing the fluid asphalt, which asphalt is applied to the web 1 or 1^a by means of rollers 12, 13 and 14, the first mentioned 95 roller dipping into the asphalt and having grooved rings 12^a thereon which serve to apply the asphalt to the web in strips. The roller 13 is merely a pressure roller to maintain the web in proper relation to the roller 12, while the roller 14 is for the purpose of removing surplus material from the rings 12^a. After passing between the rollers 12 and 13, the web travels to the mechanism for applying the animal or vegetable adhesive. 100 This mechanism comprises a tank 15 and rollers 16, 17 and 18, the rollers 17 and 18 being substantially identical with the rollers 13 and 14 respectively while the roller 16 has near each end thereof recessed rings 16^a. 105 The recessed rings 16^a are so arranged as to apply adhesive from the tank 15 immediately within the adhesive asphalt strips applied by the end rings 12^a on the roller 12. 110

By the employment of asphalt as a means 115 of connecting the plies, the resultant multi-ply paper is more pliable than if an animal or vegetable adhesive were employed; and by incorporating with the asphalt an oily substance, such as linseed oil or castor oil, 120

the asphalt is maintained in a more or less plastic condition whereby the pliability of the composite sheet is practically unaffected through temperature changes and the aging 5 of the paper. This pliability may be further enhanced by applying the asphalt in strips, and the paper itself may be embossed or otherwise specially treated for the purpose of rendering it soft or pliable before 10 the webs or sheets thereof are united.

Paper produced in accordance with my invention is sufficiently pliable to be used in the production of paper bags and to permit the mouths of such bags to be drawn in and 15 tied; while the application of the asphalt in strips not only enables the production of paper having the desirable qualities for bag construction, but accomplishes the result with a large saving of adhesive material as 20 compared with paper which is united by continuous adhesive coating.

In Fig. 5 there is shown the reinforcing thread or strip which I prefer to employ in the production of my paper. This thread 25 is a composite one, consisting of a strip of paper 19 twisted into a spiral form, with one or more pliable copper wires 20 twisted with the strip 19. The paper of which this composite thread or strip is composed ad- 30heres to the adhesive strips 5 while the copper wire serves as a binder and strength-ener to prevent the breaking of the paper thread. I have mentioned copper as the material of which the wires 20 may be com- 35 posed; but it is not essential that the wires be made of this particular material, as steel or iron wires might be used for this purpose in which case it is preferable that the wires be annealed so as to render them pli- 40 able.

As an alternative to employing either solid asphalt (or mineral adhesive) or asphalt in strips as a means for uniting the intermediate portions of the sheets, I may 45 employ alternating strips of asphalt and animal or vegetable adhesive. Furthermore, I do not propose to be limited by the term "animal or vegetable adhesive" to the use of a particular kind of adhesive, pro- 50 vided that the adhesive employed for uniting the marginal portions of the individual sheets of which the multi-ply paper is com- 55 posed and for uniting the lateral edges of such multi-ply sheets be capable of penetrat- trating the fibers and sizing of the paper.

Having thus described my invention, what I claim is:

1. A multi-ply sheet of paper comprising two plies or sheets of paper having their 60 lateral edges united by strips of mineral adhesive material and united within and adjacent to such strips by strips of animal or vegetable adhesive, and united within the last mentioned strips by means of such mineral adhesive.

2. A multi-ply sheet of paper comprising two plies or sheets of paper having their lateral edges united by strips of mineral adhesive material and united within and adjacent to such strips by strips of animal or vegetable adhesive, and united within the last mentioned strips by strips of such mineral adhesive. 70

3. Multi-ply paper comprising two plies or sheets having their lateral edges united 75 by mineral adhesive material and united within and adjacent to such mineral adhesive by animal or vegetable adhesive and united within the last mentioned adhesive by means of such mineral adhesive. 80

4. A multi-ply paper comprising two sheets or plies of paper united intermediate of their edges by means of a mineral adhesive and united closely adjacent each lateral edge by a strip of such adhesive ma- 85 terial and a strip of animal or vegetable adhesive material located adjacent to each of the last mentioned strips and between the same and the central portion of the composite sheet. 90

5. A multi-ply paper comprising two sheets or plies of paper united intermediate of their edges by means of a mineral adhesive and united closely adjacent each lateral edge by a strip of such adhesive material 95 and a strip of animal or vegetable adhesive material located adjacent to each of the last mentioned strips and between the same and the central portion of the composite sheet, there being reinforcing threads extending 100 longitudinally of and embedded within such mineral adhesive and reinforcing threads extending transversely of the first mentioned threads.

6. A multi-ply sheet of paper comprising 105 two sheets or plies of paper united at their lateral edges and at their body portions by strips of mineral adhesive material and united by strips of animal or vegetable adhesive material between such lateral edge 110 strips and the body-uniting strips, said sheets or plies having therebetween reinforcing threads extending longitudinally of and embedded within the strips of mineral adhesive and other reinforcing threads ex- 115 tending transversely of the first mentioned threads.

7. A multi-ply sheet of paper comprising a pair of plies or sheets of paper united by adhesive material and having reinforcing threads therebetween, said threads comprising each a twisted strip of paper having wire incorporated therewith. 120

8. A multi-ply sheet of paper comprising a pair of plies or sheets of paper united by 125 adhesive material and having reinforcing threads therebetween, said threads comprising a strip of twisted paper having one or more pliable metallic wires twisted therewith. 130

9. A multi-ply sheet of paper comprising two plies or sheets of paper having their lateral edges united by strips of mineral adhesive, and united within and adjacent to such strips by strips of animal or vegetable adhesive, and united within the last named strips by means of an adhesive.

10. A multi-ply sheet of paper comprising two plies or sheets of paper having their lateral edges united by strips of mineral adhesive, and united within and adjacent to such strips by strips of vegetable adhesive, and united within the last men-

tioned strips by means of spaced strips of an adhesive.

11. A multi-ply sheet of paper comprising two sheets or plies of paper having the portions thereof intermediate their lateral edges united by spaced strips of adhesive material and having their edge portions united by alternating strips of animal or vegetable adhesive and mineral adhesive.

In testimony whereof, I hereunto affix my signature.

THEODORE SCHERF.
